SNAP ACTING SWITCH

William E. Rhodes, Columbus, Ohio, assignor to Robertshaw-Fulton Controls Company, Richmond, Va., a corporation of Delaware

Application November 29, 1957, Serial No. 699,719

8 Claims. (Cl. 200—67)

The present invention relates to a snap acting device, and more particularly to a new improved snap acting electrical switch incorporating a novel improved type of arcuate operating spring of special configuration.

United States Letters Patent to E. F. Kohl Nos. 2,237,705, 2,558,219 and 2,558,258 disclose snap acting switches incorporating an arcuate operating spring of rectangular outline. The aforesaid Kohl patents disclose that the arcuate operating spring for such switches can be of normally flat thin rectangular resilient metal strip bent into arcuate form when assembled in the switch, as well as preformed. However, it was found in practice that such a normally flat rectangular spring was usually not as good as the alternative preformed arcuate spring. The reason for this is that when such an arcuate operating spring is bent from normally flat rectangular strip material upon assembly in the switch, the end loading on the spring generally causes a sharper curvature at the center of the spring arc than at its sides. This sharper curvature at the center of the arcuate spring provides a localized high stress concentration similar to a notch effect, which sometimes causes the spring to fracture in use, and generally shortens the operating life of the spring and switch in any event. Moreover, although snap switches with such normally flat rectangular springs are fully satisfactory for some applications, the switch operating characteristics such as contact pressure and operating force are not as precise or controllable for high tolerance applications, and deteriorate relatively rapidly even if initially satisfactory, compared to a like switch having a carefully made preformed arcuate spring.

Accordingly, in making switches like those disclosed in the aforementioned Kohl patents, it has been the usual commercial practice to preform the arcuate springs in such switches rather than use a normally flat spring. In making these arcuate springs in large quantities, the arcuate shape is obtained by bending the spring strip around a roller to give it a permanent deformation of desired arcuate contour, or by an appropriate stamping operation. However, in mass production of such preformed arcuate springs, it is difficult to eliminate slight variations in the length of chord between the mounting ends of the spring. Variations in chord length are also introduced by heat treatment of springs heretofore thus preformed, as amplified below. All other conditions being equal, these variations in chord length cause a slight variation from switch to switch in such characteristics as operating force, click point (i.e. operating snapover point), release force, and contact pressure. Furthermore, preforming of the arcuate springs and production control and inspection thereof are relatively costly compared to the over-all cost of making Kohl type switches. For example, for close-tolerance precision switch applications, each preformed arcuate spring is tested with a spring tester to measure its force thus increasing switch production cost significantly.

In mass production, there is frequently a slight varia-

tion from switch to switch in the spacing between the spring supporting shoulders of the actuating blade and the actuated contact blade, due to tolerances in these blade members and the switch stops which control their operating positions. For some critical close-tolerance switch applications, these variations may introduce significant changes in operating characteristics and control thereof when a preformed spring is used, because they have an effect similar to variations in the chord length of the arcuate operating springs as discussed above.

The present invention provides a new improved, lower cost precision snap acting switch combination incorporating a novel normally flat arcuate spring of special design and configuration, which effectively solves the above-discussed problems in prior arcuate rolling spring switches.

It is an object of the present invention to provide a new improved snap switch which has greatly improved operating characteristics.

It is another object of the present invention to provide an improved snap acting switch incorporating a normally flat arcuate operating spring of novel design which makes it unnecessary to use preformed arcuate springs, even for close-tolerance precision switch uses. It is a related object to provide such a switch with such a novel normally flat operating spring which eliminates variations in switch operating characteristics and control thereof heretofore encountered with preformed arcuate springs due to variations in their chord length. It is still another related object of this invention to provide for such snap acting switches a novel operating spring which renders insignificant variations in compression of the spring during operation, thereby greatly reducing the adverse effect on operating characteristics of production variations, compared to prior switches having preformed arcuate springs.

It is also an object of the present invention to provide a new improved snap acting switch including a novel operating spring of flat tempered strip material, which assumes an arcuate shape upon assembly into the switch, and has a special configuration such that the flexural stress of assembled arcuate spring is substantially the same throughout its length (mounting and effects being ignored), and does not significantly exceed the elastic limit of the spring material. It is a related object of this invention to provide such a novel normally flat operating spring which will exert the desired snapover force on the actuated contact member at the critical snapover position.

It is a further object of the present invention to provide a new improved snap acting switch incorporating a novel normally flat operating spring of special configuration which achieves higher contact pressures and has better anti-vibration characteristics compared with a similar switch having a preformed spring of rectangular outline with substantially the same operating pressure and travel of the actuating member.

It is still another object of the present invention to provide a new improved snap acting switch and a novel normally flat operating spring of special configuration which can be blanked directly from high tensile strength material, thereby obviating the steps of preforming the springs from low tensile strength material and heat treating them to raise their tensile strength, as has been heretofore done in making preformed arcuate springs. It is a related object of the present invention to provide a snap acting switch with such a novel operating spring thereby eliminating variations introduced from batch to batch and from spring to spring by heat treatment, as well as eliminating the cost of the heat treatment steps.

It is still a further object of the present invention to accomplish the foregoing objects and advantages in switch

3 performance and uniformity of characteristics with a substantial savings in production cost that may run as high as 10% of the over-all cost of the switch in lower priced, more competitive precision switch lines, whereby the present invention affords important competitive advantages.

The above-discussed and other objects and advantages of the present invention will be apparent from the following description and appended claims with reference to the drawings wherein:

Figure 1 is a plan view showing a so-called "closed type" snap acting switch embodying the present invention, with parts broken away to show underlying structure;

Figure 2 is a cross-sectional view along line 2—2 in Figure 1;

Figure 3 is a detail plan view showing the actuating and actuated blade members of the switch in Figures 1 and 2;

Figure 4 is a plan view of the novel normally flat arcuate operating spring of special configuration used in the switch of Figures 1 and 2, according to the present invention;

Figure 5 is a schematic diagram of the novel normally flat switch operating arcuate spring of this invention, illustrating the difference between (a) the total displacement of the spring mounting ends when assembled into a switch and (b) the displacement of said ends during overcenter switch operation;

Figure 6 is a schematic free body diagram illustrating a normally flat rolling spring under the action of loading imposed on it when used in a switch such as shown in Figure 1;

Figure 7 is a cross-sectional view taken along line 7—7 in Figure 6;

Figure 8 is a free body diagram of a section of the rolling spring shown in Figure 6;

Figure 9 is a graph showing one half of the symmetrical development of a constant stress, normally flat rolling spring according to the present invention;

Figure 10 is a perspective view showing a modified form of actuated and actuating blade members for use in the switch of Figures 1 and 2; and

Figure 11 is an enlarged plan view showing a modified, normally flat, constant stress rolling spring according to this invention, incorporating the same principles of design configuration as the spring in the embodiment of Figures 1—8, with modified end mounting tongues, for use with the actuating and actuated blade members shown in Figure 10.

Referring particularly to Figures 1—4, there is shown at 20 a closed type snap acting switch embodying the present invention. Switch 20 comprises a base 22 of dielectric material, which is provided adjacent one end with a bore 24 in which there is seated a metal sleeve 26 having an internally threaded bore 28. A screw 30 is threaded into the upper end of bore 28 to secure to the upper side 32 of the switch base 22 an elongated actuating blade 34 which extends within a rectangular opening in an actuated blade 36. Each of the actuating and actuated switch blades 34 and 36 has a tongue or projection 38 and 40, respectively, which extends toward the other. Each of said actuating and actuated blades 34 and 36 also has a pair of shoulders or abutments 42 and 44, respectively, in opposed spaced relation. The actuating and actuated blades may be formed as a single stamping from a sheet of flexible metal, which is provided with a hole 46 through which the mounting screw 30 extends. Alternatively, the actuating and actuated blades 34 and 36 may be formed separately if desired, with each having suitable mounting hole like aperture 46 at the mounting end thereof, in a manner obvious to those in the art. In the stamping operation, an aperture 48 is provided at the free end of the actuated blade member 36 for securing a movable contact 50 thereon.

In the assembled switch 20, an arcuate spring 52 is

5 operatively associated with the actuating and actuated members 34 and 36 in such a manner that the spring bears upon the abutments or shoulders 42 and 44 during switch operation as hereinafter more fully described. Spring 52 is made of a thin flat piece of resilient metal which is cut to the desired length and has a main portion 54 of 10 novel special configuration according to the present invention as hereinafter amplified. The spring 54 has at its ends a pair of mounting ears 56 provided with apertures 58 which loosely receive the tongues 38 and 40 when the spring is compressed into substantially semi-circular shape and assembled in the switch 20 with the ears 56 bearing upon the abutments or shoulders 42 and 44 respectively.

15 Suitable contacts 60 and 62 are arranged opposite the double movable contact 50 on the opposite sides of the actuated blade 36. The contact 60 is mounted on a suitable electrically conductive arm 64 which is secured to the switch base 22 by, and in electrical contact with, bushing 66 which is provided at its lower end with a terminal screw 68. The contact 62 is mounted in like manner on a suitable electrically conductive arm 70 which is mounted on the base 22 by, and in electrical contact with, a bushing 72 similar to bushing 66 and provided with a like terminal screw, not shown. A terminal screw 74 is similarly mounted in the lower end of bushing 26 which is electrically connected to the actuating blade 34. Thus, electrical current can flow from terminal screw 74 through the actuated blade 36 and movable contact 50 to either of the fixed contacts 60 or 62 and thence to the corresponding terminal screw at the latter contacts. As is well known in the art, if desired to make and break only one circuit, the contact 60 may be omitted and the arm 64 utilized as a stop.

20 30 35 Switch 20 is provided with a cover 76, having sides 78 which are received on shoulders 80 extending around the periphery of switch base 22. Cover 26 is provided with a bore 82 in which there is slidably mounted a reciprocable operating plunger 84, the lower end of which engages the actuating blade member 34.

40 45 50 55 60 65 As illustrated in dotted line in Figure 2, when the plunger 84 is depressed, the actuating lever 34 is moved downward, causing the spring 52 to move with a rolling action until the actuating lever 34 reaches a point at which the apertures 58 in spring 52 are substantially in alignment with the free end of actuated member 36, and the ends 56 of the spring are substantially at right angles to the actuated member 36. At this point, the actuating member 34 and the spring 52 are in overcenter "critical position," and upon further downward movement of the actuating member 34, the spring end 56 engaging the actuated member 36 applies a force or thrust action to said member 36 and snaps it upward in Figure 2, thus substantially instantaneously opening the contacts 50, 60 and closing the contacts 50, 60. Slots 58 have a somewhat greater width than the thickness of the tongues 38 and 40 to provide a non-interfering connection. The above-described switch operation may occur through engagement of the tongues 38 and 40 with the sides of the cooperating apertures 58 in the ends of spring 52 and/or through engagement of the sides of the spring ears 56 against the shoulders 42 and 44 on the actuating and actuated members, respectively. It will be noted that in the overcenter "critical position," the distance between the spring supporting abutments 42 and 44 is less than the distance between those abutments in the contact positions, so that the spring is compressed during switch operation.

70 75 The upper surface 32 of switch base 22 is slanted to permit the above-described displacement of the actuating blade 34. The actuating blade 34 is biased so that when the operating plunger 84 is released, blade 34 returns to its full-line normal position, causing the operating spring 52 to roll on the abutments 42 and 44 in the opposite direction and snap the actuated member 36 back

to normal position thereby closing contacts 50, 62 and opening contacts 56, 60.

As discussed in the introduction hereof, the arcuate operating spring in switches of this kind was heretofore generally preformed to the desired arc, and in some instances might be made of normally flat rectangular strip spring material bent into arcuate shape upon assembly; but such prior springs had certain disadvantages as noted above. In the present invention, however, the novel improved normally flat arcuate operating spring 52 now disclosed in detail provides an improved snap acting switch combination with better precision snap acting characteristics which may be more precisely controlled than heretofore.

This improved normally flat operating spring 52 has a novel configuration whereby the plan contour, and hence the cross section, of the spring is varied so that when the spring is bent into arcuate form upon assembly in the switch, (1) the stress in the spring is substantially uniform at all points along its length, and (2) the stress in no part of the spring substantially exceeds the "elastic limit" of the material in either installation or use. It has been developed that there is an optimum mathematical relationship between the width at any point along the length of the spring 52 as a function of (a) the spring length, (b) spring thickness, and (c) maximum width at the longitudinal center of the spring. And it is possible to mathematically develop and compute the optimum plan configuration of this new normally flat spring for a given material and size.

The principal limiting conditions on the arcuate spring for snap-acting switches such as here involved, include the following:

- (a) Maximum width—0.5 inch.
- (b) Minimum width—0.093 inch.
- (c) Maximum thickness—0.008 inch.
- (d) Minimum thickness—0.0015 inch.
- (e) Maximum tensile strength—300,000 p.s.i.
- (f) Minimum tensile strength—160,000 p.s.i.

(g) Radius of the rolling spring in different switches usually varies from about 0.1 to about 0.25 inch but could be larger for large size switches.

(h) Spring materials usually used include: beryllium copper; 17-7 PH stainless steel; high carbon spring steel; and Elgiloy.

The following notations are used in developing the formulas for determining the optimum plan configuration of rolling spring 52 so that the maximum stress is substantially uniform throughout the length of the bent spring when assembled in the switch, the end effects of ears 56 being ignored:

S—Flexural stress

M—Bending moment

t —Thickness of spring (see Figure 7)

b—Width of spring (see Figure 7)

$b \Big|_{\theta=\frac{\pi}{2}}$ —width of spring at $\theta=\frac{\pi}{2}$

θ —Position parameter (see Figure 6)

R—Radius of spring (see Figure 6)

P—Load on spring (see Figure 6)

I—Area moment of inertia of spring, $\frac{b^3}{12}$

E—Modulus of elasticity

Figure 6 illustrates the configuration of the subject rolling spring under the action of loading denoted by P. The differential equation of the elastic curve of this spring is defined by the equation,

$$\frac{d^2y_2}{dx^2} = \frac{M}{EI} \quad (1)$$

$$\frac{d^2y}{dx^2} = \frac{2S}{Et} \quad (3)$$

There is essentially no stress concentration due to

curvature because the thickness, t , is so small in comparison with the radius of curvature, R, of the spring. Accordingly, the flexural stress at any section location defined by θ can be computed from the well-known elementary equation,

$$S = \frac{Mt}{2I} \quad (2)$$

Simultaneous solution of Equations 1 and 2 by elimination of the factor

$$\frac{M}{I}$$

yields the equation,

$$\frac{\frac{d^2y}{dx^2}}{\left[1 + \left(\frac{dy}{dx}\right)^2\right]^{3/2}} = \frac{2S}{Et} \quad (3)$$

20 The factor

$$\frac{\left[1 + \left(\frac{dy}{dx}\right)^2\right]^{3/2}}{\frac{d^2y}{dx^2}}$$

25

is the radius of the elastic curve of the spring at any point defined by the position parameter θ . For any spring under consideration in this application, the factors E and t are both constant. Thus, for the flexural stress,

30 S, to remain constant along the spring at any value of θ , it is evident from Equation 3 that the radius of curvature must remain constant. This means that the elastic curve of the spring is a perfect circle. Stated another way, if a spring with constant E and t is forced to as

35 sume a circular configuration, then the maximum flexural stress will remain constant at all cross sections of the spring.

It is now necessary to compute the proper width contour to cause the spring to assume a circular configuration

40 under the action of the loading shown in Figure 1.

Since (from Figure 6)

$$M = PR \sin \theta \quad (4)$$

and

$$\frac{\frac{d^2y}{dx^2}}{\left[1 + \left(\frac{dy}{dx}\right)^2\right]^{3/2}} = \frac{1}{R} \quad (5)$$

50 then Equation 1 can be rewritten as

$$I = \frac{PR^2}{E} \sin \theta \quad (6)$$

If I is known at some position, say at

$$\theta = \frac{\pi}{2}$$

55 then from Equation 6,

$$I \Big|_{\theta=\frac{\pi}{2}} = \frac{PR^2}{E} \quad (7)$$

60 Equation 6 can now be expressed as

$$I = I \Big|_{\theta=\frac{\pi}{2}} \sin \theta \quad (8)$$

65 Since

$$I = \frac{b^3}{12}$$

70 and t is constant, then Equation 8 can be expressed as

$$b = b \Big|_{\theta=\frac{\pi}{2}} \sin \theta \quad (9)$$

Equation 9, then, defines the required width contour.

75 From the foregoing, the following formula relationships are applicable to design the optimum plan configura-

tion for operating spring 52 according to the present invention:

(1) The maximum thickness of spring to avoid excessive flexural stresses so that the elastic limit is not exceeded can be computed from the equation,

$$t = \frac{2SR}{E} \quad (10)$$

where S is the yield point stress of the material. If a thickness in excess of that indicated by Equation 10 is used, permanent deformation of the spring will occur.

(2) The width, b , of the spring can then be determined from Equation 9 if the maximum width, i.e.

$$b \Big|_{\theta = \frac{\pi}{2}}$$

is known or assumed.

(3) Finally, if desired, the resulting actuating force P can be computed from Equation 7.

Following is an example calculation for the detailed plan design of a typical normally flat spring 52 according to the present invention:

Data:

$$S_{max} = 300,000 \text{ p.s.i.}$$

$$R = 0.200 \text{ inches}$$

$$E = 30,000,000 \text{ p.s.i.}$$

$$b \Big|_{\theta = \frac{\pi}{2}} = 0.250 \text{ inches}$$

$$(1) \quad t = \frac{2SR}{E} = \frac{2 \times 300,000 \times 0.200}{30,000,000} = 0.004 \text{ inch}$$

$$(2) \quad b = b \Big|_{\theta = \frac{\pi}{2}} \times \sin \theta = 0.250 \sin \theta$$

Computational schedule

θ Degrees	θ Radians	Developed Length, $R\theta$ Inches	$\sin \theta$	b Inches
0	0	0	0	0
10	.17453	.0349	.17364	.0434
20	.349060	.0698	.34202	.0856
30	.52359	.1047	.50000	.1250
40	.698120	.1396	.64270	.1607
50	.872650	.1745	.76604	.1915

90	1.47077	.3142	1.00000	.2500

(3)

$$I \Big|_{\theta = \frac{\pi}{2}} = b \Big|_{\theta = \frac{\pi}{2}} \times b^3 = \frac{0.250(0.004)^3}{12} = 1.3333 \times 10^{-9} \text{ inches}^4$$

$$P = EI \Big|_{\theta = \frac{\pi}{2}} = \frac{30 \times 10^6 \times 1.3333 \times 10^{-9}}{(0.200)^2} = 1.000 \text{ pound}$$

The completed design is shown in Figure 4 of the accompanying drawings.

In designing the novel constant stress, special configuration operating spring 52 of this invention, the "elastic limit" or "proportional elastic limit" is taken for the value of S_{max} to compute the varying width and cross sectional area along the length of the spring by the above-disclosed formulas. This eliminates or minimizes set in the spring 52 when it is assembled in the switch, so that it would return to normally flat shape if it were removed from the switch assembly. However, due to the thickness of the spring 52, it is difficult to entirely avoid set in all springs and especially those of maximum thickness. However, it has been found that it is not deleterious if the spring takes a small permanent set when assembled so that it will not return completely to the preassembled normally flat shape. In general,

springs may have set within limits which will provide desired uniformity between springs with respect to uniform loading on the actuating and actuated members (34 and 36) of the switch. The limit to such set without objectionally adverse effects can be determined for given switches by routine experimentation. The spring thickness and/or material (which determines S_{max}) can be appropriately changed in the light of the above-discussed formulas to avoid excessive set.

Referring to the schematic drawing in Figure 5, a normally flat spring according to the present invention is indicated at 52c. The notation "total travel" designates displacement of the mounting ends of the spring 52c from flat position to minimum chord in the overcenter "critical position" during switch operation. The displacement of said spring mounting ends with respect to each other in contact position (e.g., as in Figure 2) to minimum chord in said overcenter "critical position" is designated as "operating travel." It will be noted that the ratio of "operating travel" to "total travel" is quite small in the case of the normally flat, constant stress spring 52 of this invention. However, in prior switches using a preformed arcuate spring, the ratio of "operating travel" to displacement of the mounting ends of the preformed spring when assembled into the switch (hereinafter called "assembly travel") is large. "Assembly travel" is a major determinant of switch operating characteristics when a preformed arcuate spring is used, so that a considerable variation in switch operating characteristics results from a small variation in "operating travel," e.g., due to tolerance variations in stamping of actuating and/or actuated members, 34 and 36, or the positioning of stops or contacts. Thus, the new normally flat, special configuration, constant stress spring 52 renders variations in operating travel relatively insignificant and thereby greatly reduces the adverse effects of such variations on precision switch characteristics.

Similarly, in prior switches incorporating preformed arcuate springs, small production variations in the chord between the mounting portions of the spring (corresponding to the slotted portions 56 of spring 52), introduce substantial differences in switch characteristics such as contact pressure, operating force, and resistance to contact chatter under vibration. Likewise, for a given spring chord, substantial differences in operating characteristics are introduced by small variations in the spacing between the spring supporting abutments 42 and 44 due to production tolerances, stamping of the actuating and actuated blades, and in the positioning of blade stops. In the new improved switch of the present invention embodying the above-described novel constant stress, normally flat spring 52, these shortcomings are substantially eliminated due to the small ratio of the size of such variations to the "total travel" of the spring ends.

With prior preformed arcuate springs, as the ratio between the length of the chord across the mounting ends of the unassembled spring and the spacing between the spring supporting abutments on the actuating and actuated members is increased, the contact pressure force and snap acting thrust exerted on the actuated blade are both increased. Therefore, an increase in this ratio has sometimes been resorted to in order to increase the contact pressure, snap acting spring thrust, and vibration resistance in prior arcuate spring switches of a given size. However, this expedient increases the stress at the center of the spring during switch operation and frequently results in a bend in the spring which adversely affects operating characteristics. As an alternative, therefore, designers sometimes resorted to a thicker spring in which this chord ratio was smaller. However, in practice it is found that use of a heavier spring creates problems because its force is not subject to the precise control required for close tolerance precision switches, excepting when the spring operates between very close limits. Another advantage of the novel stress con-

control, normally flat, operating spring 52 of this invention is that it is possible to provide an increased amount of flexure, with resulting lower operating force and higher contact pressure, without over-stressing the spring and thereby avoid adversely affecting operating characteristics.

Higher forces are achieved with material of the same thickness for constant stress springs of this invention as compared to the preformed or chorded. This is because all of the spring is worked at high stress while the preformed or chorded spring has high stress only in localized areas thus much of the spring is not fully utilized. From an energy point of view, more energy is stored in the constant stress spring of similar operating force because it has been compressed through a larger distance. Likewise more energy is available to propel switch parts since the force does not fall off as rapidly with expansion as for the preformed or chorded spring.

This invention thus achieves a wider range of control of switch characteristics than was possible with prior preformed arcuate springs.

It has been found that the contour of the novel controlled stress, arcuate spring 52 of this invention (i.e., the width at given points along the spring for a given material, spring length, and thickness) can be varied slightly from the optimum dimensions determined by the above-disclosed formulas, while still retaining the essential features and advantages of the above-disclosed invention. The degree that the width at each point along the length of the spring can be varied from the optimum width computed according to the above formulas, and more especially Equation Number 9, can be determined by routine experimentation and is governed to large extent by the factors discussed above in connection with slight permissible set.

In commercial practice, the springs 52 are stamped to their special outline with dies of corresponding contour. In order to use lower cost dies, the spring configuration plotted according to the above formulas, especially Equation 9, is substantially reproduced as closely as possible by a composite curve made up of a series of circular arcs substantially coinciding with the plan contour of said spring according to Equation 9. The stamping dies thus can be cut on a radius, according to practices known in the die making art.

It will be apparent that the ears 56 provided for mounting the spring in the switch necessitate some departure from the optimum spring configuration according to the above-discussed formulas. To a certain extent, end effects due to provision of these ears may be ignored. The size of ear dimensions designated x and y in Figure 9 is important, however, especially in small size springs, e.g., a $\frac{1}{10}$ " ear on a $\frac{1}{10}$ " maximum width spring has a much greater effect on switch characteristics causing more of a departure from the theoretical optimum than a $\frac{1}{10}$ " ear on a spring of .375 inch maximum width. The maximum size of the ear can be determined by empirical tests. In most switches the size of the ear can be designed as the minimum to satisfy mechanical requirements based on the dimensions of tongue receiving slots 58 (Figure 4).

In Figures 10 and 11 there is shown another embodiment of this invention which illustrates that the desired variation of spring width, and hence spring cross section, along the spring length, may be obtained by specific means differing from that employed in the above-described preferred embodiment of Figures 1-9, but utilizing the same principle. For clarity, parts of this embodiment corresponding to like parts in the embodiment of Figures 1-9 are identified with like numerals plus the subscript a .

Referring especially to Figure 11, there is shown a spring of rectangular outline 52a with a central portion removed leaving an aperture with curved sides having a configuration plotted according to Formula No. 9 above,

excepting for the spring mounting ends identified at 56a. As will be apparent from Figure 11, for each value of $R\theta$ (proceeding from the spring ends towards its center) a distance equal to

$$\frac{b}{2}$$

according to Formula 9 is plotted from the sides of the spring towards the center, to develop the side curves 90 of the central cut-out portion. The end mounting portions 56a are provided similarly to mounting ears 56 in the Figures 1-9 embodiment, and have end mounting notches 58a. The distance x' from the center line of notches 58a and the mounting ears 56a of spring 52a is determined by routine experimentation according to the principles discussed above in connection with the size of the dimensions x for ears 56 in the embodiment of Figures 1-9.

It will also be apparent from Figures 10 and 11 that the new and improved snap acting switch and spring according to this invention need not use a tongue and groove connection such as in the switch embodiment of Figures 1-9. Thus, for example, referring to Figures 10 and 11, the spring 52a is provided at its mounting ends 56a with a plurality of notches 58a extending inward from the spring sides for receiving the projections 38a and 40a on the actuating and actuated blades 34a and 36a, respectively, when assembled in the switch.

It will also be apparent to those skilled in the switch art that the above-described novel special configuration, normally flat, stress-controlled operating spring 52 or 52a of this invention can be incorporated in an open type switch such as disclosed in Figures 1-3 of the above-identified Kohl patents.

Heretofore, preformed arcuate springs for switches of this type have been formed to the desired arcuate shape from a low tensile strength material of say 100,000 p.s.i., and then heat-treated to raise the tensile of the spring to approximately 180,000 p.s.i. in a typical design. This heat treatment varies the spring chord and thus the forces the spring will exert on the actuated and actuating members in an assembled switch, thereby causing variations in operating forces and characteristics, from spring to spring in a given heat-treating batch, and from batch to batch. This method of spring production has been used heretofore because it has not been practical to preform arcuate spring directly from high tensile strength material to the desired chord. However, the novel configuration, constant stress, normally flat arcuate spring of this invention is blanked directly from high tensile strength material such as 180,000 p.s.i. beryllium copper or 300,000 p.s.i. Elgiloy. Thus, besides providing more uniform switch characteristics, which is the primary aim, this invention results in substantial production savings due to these process simplifications alone.

The novel special configuration, stress-controlled, arcuate spring of this invention provides substantial savings in spring production costs which cut the over-all cost of an entire switch unit as much as 10%, especially in lower priced, more competitive switches.

The springs 52 or 52a of this invention are bent into arcuate form upon assembly into the switch and special tools may be provided for doing this.

It will be apparent from the foregoing that the present invention provides a new improved rolling spring snap switch incorporating a novel improved, constant stress, normally flat, arcuate spring of special plan configuration and predetermined cross sectional variation along its length; which achieves new improved results and advantages in precision switch operating characteristics and control thereof over prior arcuate rolling spring switches; and that the same solve important shortcomings of such prior switches, and achieve other objects and advantages as discussed in the introduction of this specification, and otherwise developed herein.

The invention may be embodied in other specific forms

without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A snap acting switch comprising: a switch body; an actuating member on said body and having tongue means on one end; an actuated member on said body, having at least one movable contact thereon and having tongue means on one end in oppositely disposed relation to said tongue means on said actuating member; at least one fixed contact on said body in cooperating relationship with, and adapted to be engaged by, said movable contact on said actuated member; an arcuate operating spring of flexible relatively flat material of substantially uniform thickness having a mounting portion adjacent each end thereof, aperture means on each mounting portion being larger than and loosely receiving the tongue means of said actuating and actuated member whereby movement of said actuating member causes said spring to move with a rolling action and whereby upon actuation of said actuating member through critical position in substantial alignment with said actuated member, the spring snaps said actuating member and the movable contact thereon in a direction opposite to the movement of the actuating member to effect switch operation; said spring being unformed prior to assembly in the switch and having a plan contour such that the width of spring material progressively decreases along its length from a maximum at the center thereof so that no part of the arcuate spring substantially exceeds the elastic limit of the spring material and said spring has a substantially constant bending stress throughout its length, end effects at said mounting portions being ignored.

2. A snap acting switch as defined in claim 1, wherein the maximum thickness of said spring does not exceed substantially the value of t computed according to the equation,

$$t = \frac{2SR}{E}$$

where t is the thickness of the spring, S is the yield point stress of the spring material, R is the radius describing the arcuate form of said operating spring, and E is the modulus of elasticity of the spring material.

3. A snap acting switch as defined in claim 1, wherein the plan contour is such that the width at each point along the length of the spring excepting at said mounting

portions is substantially the value of b calculated according to the equation,

$$b = b \left|_{\theta=0} \right. \sin \theta, \text{ where } b \left|_{\theta=0} \right. = \frac{\pi}{2}$$

5 is the width of the spring when θ equals

$$\frac{\pi}{2}$$

and where θ is the angle defining the position parameter 10 of said operating spring.

4. A snap acting switch as defined in claim 3, wherein the central portion of said spring has a double convex plan outline with end mounting ears.

5. A snap acting switch as defined in claim 3 wherein 15 the central portion of said spring is cut out providing an aperture of double concave plan outline.

6. A snap action device for a switch comprising an actuating member, an actuated member, a flexible operating spring having a semi-circular portion operably disposed between said members and mounting end portions, 20 abutment means operatively interconnecting each mounting end portion with adjacent ends of said actuating and actuated members whereby movement of actuating member causes said spring to move with a rolling action, means for moving said actuating member through a critical position relative to said actuated member whereby 25 said spring causes said actuated member to move with a snap action, the semi-circular portion of said spring having a plan contour of varying width which decreases from a maximum at its center to a minimum at the end portions to produce a substantially constant bending stress in the semi-circular portion at each point along its length, and the width of the semi-circular portion varies according to the equation

$$b = b \left|_{\theta=0} \right. \sin \theta, \text{ where } b \left|_{\theta=0} \right. = \frac{\pi}{2}$$

30 is the maximum width of the spring, where b is the width at a position parameter along the semi-circular portion and θ is the angle measured from one of the end portions to such position parameter.

7. A snap action device as defined in claim 6 wherein the semi-circular portion of said spring has a double convex plan outline.

8. A snap action device as defined in claim 6 wherein 45 the semi-circular portion of said spring is cut out providing an aperture of double concave plan outline.
